UNITED STATES PATENT OFFICE.

JOHN NONNENBACHER, OF NEW YORK, N. Y.

DESIGN FOR PICTURE-FRAMES, &c.

Specification forming part of Design No. 6,995, dated November 11, 1873; application filed September 19, 1873.
[Term of Patent 3½ years.]

To all whom it may concern:

Be it known that I, JOHN NONNENBACHER, of the city, county and State of New York, have invented a Design for Mirror and Picture Frames, Cornices, &c., of which the following is a specification:

The nature of my design is fully illustrated in the accompanying drawings, to which reference is made, and in which—

Fig. 1 is a cross-section, and Fig. 2 a face elevation.

a represents a portion of the molding, projecting well forward, and ornamented with a series of raised oak leaves with acorns, in gilt. *b* represents a recessed or concave molding ornamented as shown, ornaments raised, and

the molding, &c., gilt. *c* represents a slightly convex molding, ornamented, flat, the ground-work being silvered over the gilt, leaving the ornamentation bright in gilt. *d* represents a raised ornamentation on a flat surface, also in gilt. *e* is an ogee-molding, plain and silver gilt, and all the remainder of the moldings, as shown, are silver-gilt.

What I claim as my invention is—

The design for frames, cornices, &c., as herein shown and described.

JOHN NONNENBACHER.
